VACUUM POWER AND WATER RECLAIMER
DEVICEVincen P. McVoy, Mobile, Ala., assignor, by mesne
assignments, to Vacuum Engine Corporation,
a corporation of DelawareApplication November 28, 1934, Serial No. 755,236
Renewed September 3, 1936

6 Claims. (Cl. 60—95)

The present invention relates to power plants, and has for an object to provide a device of this character wherein the usual proportion of water is reclaimed from used steam and wherein additionally the heat of condenser cooling water is used for evaporating from the condenser cooling water a sufficient amount of fresh water to make up the loss in the condensation of the used steam, and also to obtain power for driving an engine in the evaporating of the fresh water from the condenser cooling water.

Another object of this invention is to provide an absolute pressure chamber for the treatment of the waste hot water from the condenser to take off vapors which increase the absolute pressure on the pressure side of the piston of an engine, and to utilize the differential absolute pressures at the opposite sides of the piston for operating the engine.

With the foregoing and other objects in view, the invention will be more fully described hereafter, and will be more particularly pointed out in the claims appended hereto.

In the drawings:

Figure 1 is a diagrammatic elevation of a device constructed according to the present invention.

Figure 2 is a fragmentary sectional view through the upper end portion of the engine of Figure 1, showing the valve structure, and

Figure 3 is a sectional diagrammatic view of the condensing and vaporizing portion of the device.

Referring to the drawings, 25 indicates a low pressure steam boiler of any suitable type from which is carried a steam pipe 26 leading to the intake 27 of the valve chamber of an engine 28. The engine 28 may be of any suitable type, such as a reciprocating piston steam engine with the exception of an improved valve structure, as is disclosed in my copending application Serial No. 755,237 filed November 28, 1934, now Patent No. 2,040,865.

Reference is now made to Figure 2, taken from the above referred to application in which 28 indicates the engine or cylinder having a piston 26' therein. The piston has a rod 27' extending through the bottom of the cylinder 28. At one side, the cylinder 28 has a port block 32' having opposite end ports 33' and 34' therein which open through the outer side of the block 32'. Between the outer ends of the ports 33' and 34' is an outlet or exhaust port 29 which leads to a source of a relatively low absolute pressure, such as about one pound absolute pressure obtained from the condenser 30 to which the exhaust port 29 is connected as shown in Figure 1.

A steam or valve chest 36' is secured against the block 32' and is provided therein with a pair 60 of slidably interfitting valve pistons 37' and 38'.

A third valve piston 39' is fixed to the upper end of the valve chest 36', and has an inlet stem or pipe 53, and engages in the bore of the intermediate slidable valve piston 38'. The valve pistons are each provided with sealing rings 40' advantageously mounted thereon to seal the valve pistons in the valve chest and consecutively within one another. The outer valve 37' has near each end an annular row of openings 41' therein located with sealing rings 40' at opposite sides of each row of the openings.

The intermediate valve piston 38' has a plurality of openings 42' therein slightly below the central portion of the valve piston and both of the valve pistons 37' and 38' are open at their upper ends while the lower end of the outer valve piston 37' is also open. The intermediate valve piston 38' is shorter than the outer valve piston 37' and is adapted to be shifted therein while the inner valve piston 39' is stationary and engages in the upper end only of the intermediate valve piston 38'.

The intermediate valve 38' has a valve rod 43' which passes downwardly through the valve chest 36' to the valve operating mechanism. The outer valve piston 37' has a sleeve 46' extending about the rod 43' and which is also connected to the valve operating mechanism. As shown in Figure 2 the ends of the ports 33', 34' and 29 extend annularly about the inner wall of the valve or steam chest 36' so as to surround the valves in the chest. The inner piston valve 39' is hollow to provide a supplemental intake passage into the steam chest 36' while the outer wall of the steam chest has a longitudinal passage 52' 35 interconnecting the opposite ends of steam or vapor chambers 53' of the steam chest.

The exhaust or outlet pipe 29 leads from the engine into the intake of a main condenser 30 which is a source of very low absolute pressure, such as about two pounds; the condensate being carried off through a pipe 31 leading to an air or vacuum pump 32 and thence through a pipe 33 into a heater 34. The hot condensate passes out of the heater 34 through a pipe 35 to a feed pump or the like returning the water to the boiler 25 under pressure of a pump 36. From the top of the heater 34 the gases are taken off by a pipe 37 leading to a separating tank 38, and from the tank 38 through a pipe 39 to the fire box of the boiler 25.

The water pump 36 may be operated by waste exhaust steam from any suitable source entering the steam cylinder of the pump through a pipe 40 and out of an exhaust pipe 41 which may be carried into the heater 34, as shown in Figure 3. From the heater 34 the exhaust steam is carried through a pipe 42 into the condenser 30.

Surface water enters the condenser 30 for cooling the same through a pipe 43 and leaves the 60

condenser through a pipe 44 which may lead back to the source of water or waste. A valve 45 is disposed in the pipe 44 to control passage of the waste water therethrough and between the valve 45 and the condenser 30 the pipe 44 has a by-pass pipe 46 with a heater 47 therein to receive a desired proportion of the waste water. The heater 47 has a supply pipe 48 connected to the spraying head 38' of an evaporator cylinder 49 disclosed in my copending application Serial No. 755,235 filed November 28, 1934, now Patent No. 2,027,395. The cylinder 49 has a pipe 50 leading therefrom between its ends which leads to the pump 32 for maintaining a low vacuum of about five inches on the cylinder 49. The pipe 50 may be directly connected to the pump 32, as shown, or in any other suitable manner. A diaphragm regulating valve 51 is placed in the pipe to regulate the vacuum on the evaporator cylinder 49. The return by-pass pipe 52 leads from the bottom of the evaporator cylinder 49 to the waste outlet pipe 44 at a point outwardly of the valve 45. The cylinder 49, in actual use, is elevated proportional to the low absolute pressure desired to prevent priming back into the engine through the vapor pipe 53 and to provide a gravity column in the pipe 52 for the proper discharge of the water accumulating in the bottom of the cylinder 49, known as surface water. The vapor pipe 53 leads from the top of the cylinder 49 to the supplemental intake, or the interior of the fixed valve piston 39' of the engine 28.

In the operation of the engine, the condenser 30, which is a source of relatively low absolute pressure, is connected to the exhaust line 29 of the engine and thus places the interior of the steam chest 38' in the condition of a relatively low absolute pressure. As shown in Figure 2, the piston 28' is in its upper dead center position and the valve gear of the engine is so arranged that at this time the upper openings 41' of the outer valve sleeve or piston 37' are in partial communication with the upper fluid distributing port 33' which leads to the top of the cylinder 28. As the upper end of the valve piston 37' is open steam from the pipe 27 and upper chamber 53' enters the piston 37' and passes out through the openings 41' into the annular space between the adjacent packing rings 40' and through the passage 33' to the top of the piston 26'. This imparts an initial impulse to the piston 26' and starts the latter on its downward stroke or movement. During the cycle of operation, after a short downward movement of the piston 26' the openings 41' are cut off by a first upward movement of the intermediate valve piston 38', the latter also closing the port 33' and the steam above the piston 26' is permitted to expand for a further short movement of the piston 26'.

The exhaust port, or low absolute pressure line, 29 is gradually opened to a greater extent during the operation of the valve pistons 37' and 38' so as to establish the low absolute pressure condition created by the condenser 30 at the underside of the piston 26'.

When the steam expands substantially to its full working capacity above the piston 26' the valve pistons 37' and 38' move into such relative positions that the valve openings 41' are uncovered by the upper end of the intermediate valve piston 38' and establish communication between the intermediate annular space of the middle valve piston 38'; its openings 42' and the interior of the inner fixed valve piston 39' so that

the pressure fluid from the vaporizer 49, which is less than the relatively high pressure in pipe 27 and greater than the exhaust back pressure in the displacement line 29, will be delivered through the engine ports 42', 41' and 33' into the cylinder 5 at the upper side of the piston 26' and thereby relieve the tendency to produce a vacuum at that side of the piston.

Thus it will be seen that the piston will continue its movement due to the differential in pressures between the vaporizer 49 and the condenser 30.

In starting up the power plant, surface water is forced through the pipe 43 into the condenser 30 and the valve 45 is opened so as to allow the 15 waste water from the condenser 30 to pass out of the discharge pipe 44 as waste. The valve in the steam pipe 26, which leads from the boiler 25, is opened to admit steam in the usual manner to the engine 28 for starting the operation of the 20 engine as specifically above set forth. The operation of the engine starts the operation of the air or vacuum pump 32 so as to reduce the absolute pressure in the condenser 30 and the pipe 29 which leads from the engine 28 to the condenser, 25 thus producing a low absolute pressure in the engine 28, the pipe 29 and the condenser 30. As the absolute pressure decreases in the pipe 29, the valve in the steam pipe 26 is proportionately 30 closed as when the engine is running normally but a slight volume of steam is required, sufficient only to prevent formation of a vacuum on the pressure side of the piston.

With reference to Figure 1, steam from the boiler 25 is admitted through the pipe 26 and its 35 valve at approximately four pounds above atmospheric pressure, which is about nineteen pounds absolute pressure, to the engine 28. This gives the initial downward thrust to the piston 26' of the engine. The second inlet or vapor line 53 40 from the vaporizer 49 provides a source of high absolute pressure, such as about twelve pounds absolute pressure and admits a continued downward movement of the piston 26'.

The outlet 29 of the engine provides a very 45 low absolute pressure, such as about two pounds from the condenser 30 where the vapors are withdrawn from the engine 28 and condensed by the cooling water in the condenser water circulating pipe 43, 44 wherein the water may enter at about 50 80° F. and passes from the condenser at approximately 105° F. This condenser water may be wasted through the valve 45 and the waste pipe 44. The condensed vapor in the condenser 30 is drawn off through the pipe 31 and pump 32 and 55 back to the boiler 25 through the pipe 35.

As the surface water passing through the condenser 30 is heated by absorbing heat from the exhaust vapors of the engine 28, the valve 45 is gradually shut off to the desired extent so as to 60 by-pass a desired amount of the hot condenser cooling water through the pipe 46, heater 47, if desired to raise the waste condenser water to approximately 200° F., pipe 49 and into the evaporator cylinder 49. The hot waste water 65 entering the upper portion of the cylinder 49 is separated from its vapors under the low absolute pressure tension which is produced in the pipe 53 connected to the supplementary inlet of the engine 28. The residue water in the evaporator 70 cylinder 49 is carried from the bottom thereof through the pipe 52 to the discharge or waste pipe 44 at a point beyond the valve 45. The heater 47 may or may not be used, and when used may receive its heat by exhaust steam from 75

some adjacent engine or unit of the plant. It is thus apparent that the engine 28 is operated with a considerably reduced fuel consumption as it reclaims a relatively large proportion of its energy by utilizing the vapors produced in the evaporator cylinder 49 and the utilization of the usually lost heat in the waste water circulated through the condenser 30.

It is well known that operating under the influence of absolute pressures there is a limitation of 14.7 pounds per square inch, absolute pressure. This natural condition would necessarily restrict the obtaining of any effectual horse power in an engine except for the fact that the piston area of the engine may be enlarged considerably in proportion to the horse power desired so as to obtain the necessary results for efficient operation.

Also, the engine may be built up of any number of cylinders and pistons operable on a single crank shaft to build up the necessary horse power. In using this low absolute pressure power plant it will be noted that at the intake side of the engine there is an absolute pressure which is relatively high and that owing to this and to the fact that there is a relatively low absolute pressure at the exhaust, back pressure or choking in the transfer of the intake steam is eliminated, and thus the engine is free to operate under a lower absolute condenser pressure and the full working capacity of the absolute pressure is thus obtained with respect to the entire cross sectional area of the piston.

What is claimed is:—

35 1. In a power plant, an engine having a steam chest provided with separate and independent high and low pressure steam inlets and a single outlet, a source of steam under pressure connected to the high pressure inlet of the steam chest for initially starting the piston of the engine, a source of vapor under lower pressure connected to the low pressure inlet of the steam chest for continuing the piston stroke without producing a vacuum on the pressure side of the piston which would retard the movement of the piston, a condenser connected to the outlet of the steam chest, said condenser having a cooling water circuit, a vaporizer connected in said cooling water circuit, and a heater in said circuit between the condenser and the vaporizer to heat the water entering the vaporizer and supply said source of vapor for the engine.

2. In a power plant, a low pressure steam boiler, an engine having a steam inlet connected to the boiler for initially moving the piston of the engine and having a vapor inlet, a condenser connected to the exhaust outlet of the engine and having a cooling water circuit therein for withdrawing and condensing vapors from the engine and operating the piston by differential pressures between the opposite sides of the piston of the engine, and an evaporator connected to the outlet side of the condenser cooling water circuit and to the said vapor inlet of the engine for collecting vapors from the waste condenser cooling water and supplying the vapor at a low pressure to the pressure side of the piston of the engine and prevent formation of vacuum at the said pressure side of the piston.

3. In a power plant having an engine with a steam inlet, a vapor inlet, a vapor exhaust, and valve means for cutting off the steam supply and opening the vapor inlet upon initial movement of the pistons of the engine, a source of steam con-

nected to the steam inlet of the engine to start the movement of the piston, an evaporator connected to the vapor inlet to supply vapor to the engine when the steam is shut off and prevent formation of a vacuum at the pressure side of the piston, and a condenser connected to the vapor exhaust of the engine to withdraw vapor therefrom and having a cooling water circuit for condensing the vapors from the engine and effecting a low absolute pressure in said exhaust to move the piston by the differential pressures at opposite sides of the piston, said water circuit being connected to the evaporator to collect vapors from the condenser waste water for supplying said vapor inlet of the engine.

4. In a power plant, an engine having a piston, a controlled source of steam supply connected to the engine for operation on the pressure side of the piston of the engine, a water cooled condenser connected to the exhaust of the engine, an exhaust pump connected to the condenser to create a low absolute pressure in the condenser and the exhaust of the engine, an evaporator connected to the outlet of the cooling water circuit of the condenser, and a vapor pipe leading from the evaporator to the inlet of the engine for preventing formation of a vacuum at the pressure side of the piston when the steam is shut off.

5. In a power plant, an engine, a boiler having a steam connection to the engine at the pressure side of the piston of the engine for delivering a restricted volume of steam to the engine, a condenser connected to the exhaust of the engine at the opposite side of the piston, a pump connected between the condenser and the boiler and operable by the engine for reducing the pressure in the condenser to a relatively low absolute pressure and returning the condensate to the boiler, an evaporator connected to the cooling water circuit from the condenser for separating vapor from the waste hot water, and a vapor pipe leading from the evaporator to the engine at the pressure side of the piston to supply vapor under a high absolute pressure thereto and prevent formation of a vacuum at the pressure side of the piston.

6. A power plant comprising a boiler for generating steam at low pressure, an engine having an initial steam inlet and a secondary vapor inlet and having an exhaust, said engine connected to said boiler at the steam inlet of the engine, a condenser having a water cooling circuit therein and connected to the exhaust of said engine for withdrawing vapors therefrom and condensing the vapors to effect a relatively low absolute pressure in the exhaust of the engine, a suction pump connected to the condenser for withdrawing the condensate, a heater connected to the pump for collecting vapors from the condensate, boiler return pipes connected to the heater for withdrawing the heavy condensate to the boiler and returning the vapors to the boiler and including a separator for entrapping water from the vapors, a heater connected to the outlet side of the condenser cooling water circuit for raising the temperature of the hot water from the condenser, and an evaporator connected to the heater for receiving the heated waste water therefrom and connected to said vapor inlet of the engine for delivering vapor collected from the condenser waste water in the evaporator and prevent formation of a vacuum at the pressure side of the piston in the engine.

VINCEN P. McVOY.
